UNITED STATES PATENT OFFICE.

FRANCIS H. YOST, OF PHILADELPHIA, PENNSYLVANIA, ASSIGNOR OF ONE-HALF TO WILLIAM H. HARRIS, OF SAME PLACE.

DESIGN FOR A PUZZLE-BODY.

SPECIFICATION forming part of Design No. 23,359, dated June 12, 1894.

Application filed April 4, 1894. Serial No. 506,349. Term of patent 3½ years.

To all whom it may concern:

Be it known that I, FRANCIS H. YOST, a citizen of the United States, residing in the city and county of Philadelphia, State of Pennsylvania, have invented and produced a new and original Design for the Body of a Puzzle, of which the following is a specification, reference being had to the accompanying drawings, forming part thereof.

10 The leading feature of my design for the body of a puzzle is a field with a radial passage, tortuous passages on the sides thereof, and tongues projecting into the tortuous passages.

15 Figure 1 represents a plan view of the body of a puzzle embodying my design. Fig. 2 represents a transverse section thereof.

Similar letters of reference indicate corresponding parts in the two figures.

In the drawings: A designates the body of the puzzle, the same having on the field B thereof, the radial passage C, the tortuous passages D on the sides thereof, and the tongues E, which project into the tortuous passages.

20 What I claim is—

25 The design for the body of a puzzle, substantially as shown and described.

FRANCIS H. YOST.
